BUFFING WHEEL

John F. White, Bloomington, Ill.

Application August 12, 1938, Serial No. 224,598

5 Claims. (Cl. 51—193)

My invention pertains to certain novel and improved structural and functional betterments in ventilated or cooled buffing-wheels and their mountings, one leading object of the invention being to provide a new type of structure which more adequately controls the temperature of the fabric-elements of the wheel while in operation, and more particularly the inner or middle portion of the wheel.

10 Another aim of the invention is to supply a buffing-wheel of the style referred to which is relatively simple in construction, and hence comparatively economical to manufacture.

15 A further purpose of the invention is the provision of a buffing-wheel which is efficient in operation and which is unlikely to become damaged or injured in ordinary service.

An added design or intention of the invention is the furnishing of a buffing-wheel which may 20 be mounted on, and demounted from, its supporting and operating spindle or shaft with ease and dispatch.

To enable those acquainted with this art to understand the invention fully, two present desirable embodiments of the same have been illustrated in the accompanying drawings to which reference should be had in connection with the following detailed description, and, for simplicity, like reference numerals have been provided 30 throughout the several views to designate the same parts of the construction.

In these drawings:

Figure 1 is a central, vertical section through one type of the new buffing-wheel;

35 Figure 2 is a section through the wheel on line 2—2 of Figure 1;

Figure 3 is a similar, central, vertical section through the second embodiment of the invention; and

40 Figure 4 is a section on line 4—4 of Figure 3.

Referring to these drawings, and more particularly to Figures 1 and 2 thereof, it will be perceived that in its current most preferred form, the buffing-wheel may be made from an ordinary, straight-face, pulley, modified or changed to adapt it to perform the necessary functions.

45 As is usual, such pulley has a central, apertured, supporting hub 10, a middle, circular web 11 outstanding from such hub, and an outer, cylindrical main-body portion 12 supported by the web, all three parts, 10, 11 and 12 being of metal, such as aluminum, alloy or the like, and all integral with one another.

50 So far as thus described, the structure is noth-

ing more than that of an ordinary commercial pulley.

To change or reform such pulley to adapt it to carry the fabric buffing-elements and to ventilate or cool them in suitable and adequate degree, an appropriate number of holes 13 are drilled through the central part of the portion 12 at the same time removing some of the web 11, all as is fully and clearly illustrated.

Also a suitable number of holes or apertures 10 14, 14 are drilled through the part 12 on opposite sides of the medial web 11.

In addition, the two opposite margins of the outer face of such modified pulley are provided with suitable screw-threads 15 and 16, right and 15 left hand if desired, on which may be screwed two collars or round nuts 17 and 18 which may have recesses 19 for the accommodation of the prong of a spanner-wrench by means of which the collars or nuts may be screwed and tightened 20 into place.

These collars 17 and 18 securely hold or clamp between them the inner, marginal portions of centrally-apertured fabric-buffing-elements 21, 21 which have a considerable number of radially- 25 disposed ventilating-passages 22 in their opposite faces around their central openings.

When such metal mounting and its fabric buffing-members have been applied to the operating shaft 23 with one end of the hub bearing against 30 a shoulder 24 of the shaft and a nut 25 threaded in the end of the shaft and engaging the opposite end of the hub, the buffing-wheel is ready for action upon rotation thereof by the revolution 35 of the shaft.

As will be readily understood, during the rapid rotation of the buffing-wheel, air present at opposite sides of the web, due to centrifugal force, flows or is forced outwardly through the several holes 13, 14 and through the passages 22 in the 40 sides of the fabric-members, thus adequately and properly cooling the latter elements against the otherwise destructive action of the heat generated by the buffing-operation.

45 A somewhat different type of structure is presented in Figures 3 and 4 in which case the mounting for the fabric buffing-elements comprises a hub 31, adapted to be supported and clamped on the reduced-diameter portion 32 of the drive-shaft 33, between a collar 34, on the 50 part 32 and bearing against a shoulder 35, and a nut 36 screwed on the threaded end portion of the shaft section 32.

As in the previously-described structure, outstanding from the center of, and integral with, 55

the hub is a circular web 37 forming a part of an integral with the outer portion of the mounting comprising two, end, cylindrical parts 38, 38 externally-screw-threaded at 39, 39 for the retention of complementarily-threaded collars or nuts 41, 41, having spanner-wrench prong-receiving cavities 40.

The portion of the mounting between such end-members 38, 38 is cut away or omitted at intervals to provide parallel, spaced, external, longitudinal grooves 42, 42 each open at its opposite ends at 43, 43, and, as in the case of the other type of appliance, holes 44, 44 may be provided at centers of such grooves with removal of portions of 15 the web so that air may directly enter the middle portions of such grooves from opposite sides of the web as well as at their opposite ends.

As will be readily understood, the open-center, textile-fabric buffing-members 45, 45 with permanent, radially-disposed ventilating or cooling passages 46, 46 at their sides are supported on the mounting and clamped firmly and securely between the readily-adjustable, threaded collars or nuts 41, 41 all as is clearly illustrated, and, when 25 the complete buffing-wheel, as thus constituted, is rotated at the usual high speed, air is drawn in through the grooves 42, 42 and is delivered therefrom to the several connecting passages 46, 46 through which it is discharged outwardly between 30 the fabric members, thereby maintaining the latter at a suitable temperature to preclude undue or damaging heating and burning of the cloth which is performing the buffing and polishing action.

Those acquainted with this art will understand 35 that the invention is not necessarily limited and restricted to the precise features illustrated and described and that various modifications may be resorted to without departure from the heart and essence of the invention as defined by the appended claims, which should be construed as broadly as permitted by the state of the prior art, and without the loss or sacrifice of any of the 40 benefits accruing from the employment of the invention.

45 I claim:

1. In a buffing-wheel mounting, the combination of a member having a hub adapted to be applied on the shaft designed to rotate the wheel, a substantially-central circumferential web out-

standing from said hub, and a cylindrical main body-portion supported on the outer part of said web in outwardly spaced relation to said hub, said hub having an outstanding flange at one end and an external screw-thread at its other end, a screw-threaded collar adapted to cooperate with said screw-threaded end and to clamp between said flange and collar a series of concentric open-center fabric buffing-elements, having outwardly-directed ventilating-passages at the inner portions of their sides, the middle part of said body-portion having a row of openings therethrough arranged to communicate with the ventilating-passages of said buffing-elements and opening at both sides of said web, whereby said connected 15 openings and passages afford conduits for the flow of cooling air therethrough to prevent overheating of said buffing-elements by flowing outwardly between them.

2. The buffing-wheel mounting presented in 20 claim 1 in which said main body-portion has other openings therethrough at opposite sides of said web and said first row of openings and also arranged to communicate with the ventilating-passages of said buffing-elements. 25

3. The buffing-wheel mounting presented in claim 1 in which the external surface of said main body-portion has longitudinally-arranged circumferentially-spaced grooves communicating with said row of openings and with said ventilating- 30 passages.

4. The buffing-wheel mounting presented in claim 1 in which the external surface of said main body-portion has longitudinally-arranged circumferentially-spaced grooves communicating 35 with said row of openings and with said ventilating-passages, said grooves being open at their opposite ends on opposite sides of said web.

5. The buffing-wheel mounting presented in claim 1 in which each of said openings eliminates 40 a part of said web thereby providing an opening therethrough, and in which the external surface of said main body-portion has a series of longitudinally-arranged circumferentially-spaced grooves the middle of each of which is in communication with one of the openings of said row, and in which each said groove is open at its two 45 ends on opposite sides of said web.

JOHN F. WHITE.
